UNITED STATES PATENT OFFICE.

ADRIAN J. CHAVANNES, OF DES MOINES, IOWA.

PRINTER'S DRYING-CABINET.

1,346,781.

Specification of Letters Patent. Patented July 13, 1920.

Application filed September 23, 1919. Serial No. 325,792.

To all whom it may concern:

Be it known that I, ADRIAN J. CHAVANNES, a citizen of the United States, and a resident of Des Moines, in the county of Polk 5 and State of Iowa, have invented a certain new and useful Printer's Drying-Cabinet, of which the following is a specification.

The object of my invention is to provide a printer's drying cabinet of simple, durable 10 and inexpensive construction.

A further object of my invention is to provide a printer's drying cabinet which will enable printers to dry their job printing in a short time at a minimum expense.

15 A further object is to provide a device whereby printed matter may be hardened quickly to thereby cause a more perfect finish and at the same time make it possible to quickly and easily complete a job of printing.

20 A further object is to provide a cabinet having a heating member therein and tiers of paper stock supporting racks so arranged that a circulation of heated air may be 25 passed around said supporting racks, thereby drying paper having printed matter thereon in a very short time.

25 A further object is to provide a cabinet whereby dampness and electricity may be removed from paper stock about to be used 30 for printing, thereby making the handling of the paper stock very easy, and at the same time placing the paper in such a condition that a job of printing may be done while 35 the paper stock is in its prime condition.

Still a further object is to provide a cabinet 40 for drying printed work which is provided with tiers of supporting racks which may be selectively spaced in said cabinet to accommodate various sizes of bundles of 45 paper stock, the supporting racks being removable from said cabinet so that the paper may be placed upon said racks and then be placed into the drying cabinet for drying.

With these and other objects in view my 50 invention consists in the construction, arrangement and combination of the various parts of the device, whereby the objects contemplated are attained, as hereinafter more 55 fully set forth, pointed out in my claim and illustrated in the accompanying drawings, in which:

Figure 1 shows a perspective view of my improved drying cabinet showing the doors 55 thereof in open position.

Fig. 2 shows a perspective view of one of

the removable racks which I use in supporting my paper stock, which is desired to be dried.

Fig. 3 shows a perspective view of one of 60 the guides which is used for supporting the racks shown in Fig. 2.

Fig. 4 shows a perspective view of the screen partition member which is designed 65 to be secured in the cabinet.

In the accompanying drawings I have used the reference character A to indicate generally my cabinet. The cabinet A comprises a top 10 and a bottom 11 with the side wall members 12 and a back 13. Hinged 70 to the front of the cabinet A are the door members 14 which are provided with suitable means 15, so that they may be locked and held in that position.

The cabinet is mounted on the legs 16. 75 The top 10 and bottom 11 are provided with openings 17 and 18, the purpose of which will be hereinafter more fully set forth.

Supported on the bottom or base 11 is a bracket 19, which supports the heating member 20. The heating member 20 is preferably an ordinary gas pipe having a plurality of openings therein, so that gas which may be passed into the heating member 20 may be lighted, thereby causing heat to be radiated 85 from said member.

The heating member 20 extends through the wall 12 of the cabinet and is provided with a cut-off 21.

By using the cut-off 21 I am able to regulate 90 the amount of gas which will be permitted into the heating member, thereby regulating the amount of heat within the cabinet.

Spaced somewhat above the heating member 20 is a screen partition member B which comprises a rectangular frame 22 and the screen portion 23.

The frame 22 is provided on the sides adjacent to the sides 12 of the cabinet with 100 downwardly extending flanges 24. The flanges 24 have openings 25 therein, so that the device may be detachably fixed to the cabinet.

Spaced parallel guide members 26 are 105 fixed to the sides 12 of the cabinet. The guides 26 are designed to receive and support the paper supporting racks C.

The paper supporting racks C comprise end members 27 which are fastened together 110 by spaced parallel slats 28.

The end members 27 of the paper sup-

porting racks are adapted to rest upon the guides 26.

The paper supporting racks may be placed at various intervals in the cabinet, so that 5 spaces of various sizes may be had for accommodating paper stock of various thicknesses.

It will be seen that whenever any printed matter is desired to be quickly dried, while 10 the ink is yet in its prime condition, the paper supporting racks C are taken out of the cabinet and placed close to the printing machine, so that the printed matter may be placed upon the racks.

15 As soon as the racks become filled with printed matter, they are slid into the cabinet. After the paper is placed in the cabinet, the heating member 20 is then put in operation, and the doors 14 of the cabinet 20 are closed.

The heat from the heating member 20 will pass upwardly through the screen 23 and circulate through the spaces between the slats 28 of the rack C, and around the paper 25 stock which is placed upon the racks and escape through the openings 17 in the top of the cabinet.

Cold air will be taken in through the openings 18 in the bottom and will pass upwardly around the heated member, thereby heating the air in its circulation, so that any paper stock which is in the cabinet may be quickly dried.

It is very desirable to be able to dry the 30 printed matter quickly after it is printed, because when the ink is yet fresh and it is dried quickly, a more perfect finish is obtained than were the printed matter permitted to dry by the ordinary method.

40 In this connection it might be stated that a job of printed matter may be quickly gotten out by the use of my improved printer's drying cabinet without any great amount of expense.

45 The partition member B is provided for preventing any of the paper stock, which is placed in the cabinet on the racks, from coming in contact with the heating member 20.

50 Some of the paper stock might be accidentally thrown off the racks and were this partition member not provided a fire would result.

The object of the partition member is to 55 relieve this danger.

My printer's cabinet can also be used advantageously for drying paper stock before the printing is done.

It is well known that electricity is formed 60 in the paper from dampness, and it is very hard to obtain a smooth finished printing job when the paper is damp.

In order to obtain a perfect finished printing job it is necessary that the paper be in a 65 certain condition; that is, absolutely dry.

By placing the stock in my cabinet just before use and leaving the paper in the cabinet for a few minutes, all the dampness and electricity in the paper will be removed therefrom, so that I can then proceed with 70 the printing when the paper is in the prime condition for printing, and thereby obtain a more perfect job of printing, in less time, than could otherwise be obtained.

In this connection it may be stated that 75 when a printing job is performed, and one side of the sheet is printed it becomes necessary to wait a considerable length of time before the other side may be printed upon.

This is especially true upon damp and 80 cloudy days when it is almost impossible to print the other side of the sheet without waiting four or five days.

In some printing shops where a rush job 85 is performed and it is impossible to wait the four or five hours, the printer will print the other side any way and turn out a smearable job of printing.

By the use of my cabinet after one side 90 of the sheet is printed and placed in a cabinet, then in a very short time I am able to print the other side of the sheet, and at the same time have the job completed in a very short time, and better than could be obtained otherwise.

95 Some changes may be made in the construction arrangement and combination of the parts of my device without departing from the essential features and purposes of my invention, and it is my intention to cover by my claim any modified forms of structure or use of mechanical equivalents which may be reasonably included within their scope.

100 I claim as my invention:

A printer's drying cabinet, comprising a cabinet mounted on legs; hinged door members for permitting access into said cabinet; means whereby paper supporting racks may be selectively placed in said cabinet at various distances relative to each other, whereby bundles of paper of various thicknesses may be accommodated, said racks including slats held together by end members, whereby air may pass through said rack, a heating member near the bottom of said cabinet, means for regulating the amount of heat permitted to circulate through said cabinet, a screen partition placed in said cabinet above said heating member, and below said paper supporting racks, thereby preventing any paper from accidentally coming in contact with said heating member, said cabinet being provided with openings in its top and bottom for permitting air to pass in and pass out thereby forming a circulation which, when heated, will quickly dry the paper stock on said racks.

110 Des Moines, Iowa, August 7, 1919.

115 ADRIAN J. CHAVANNES.
